Fig. 3

The diagram illustrates a magnetic circuit with the following components and labels:

- A horizontal magnetic core with a rectangular cross-section.
- A vertical magnetic core segment labeled *K* on the right.
- A circular air gap labeled *h* in the center.
- A rectangular air gap labeled *j* on the left.
- A rectangular air gap labeled *g* at the bottom left.
- A rectangular air gap labeled *p* at the bottom right.
- Two vertical rectangular air gap segments labeled *E'* on the right.
- Two vertical rectangular air gap segments labeled *E* at the bottom.
- Two circular air gap segments labeled *m* on the left.
- Two circular air gap segments labeled *n* on the right.
- Two circular air gap segments labeled *i* at the bottom.
- Two circular air gap segments labeled *e* at the bottom.
- Two circular air gap segments labeled *k* on the right.
- A vertical line labeled *x* on the left.
- A vertical line labeled *C* at the top center.
- A vertical line labeled *I* on the right.
- A vertical line labeled *J* on the right.
- A vertical line labeled *a* on the right.
- A vertical line labeled *o* on the right.
- A vertical line labeled *q* on the left.
- A vertical line labeled *r* on the left.

UNITED STATES PATENT OFFICE.

HENRY M. HARDING, OF NEW YORK, N. Y.

TELPHER.

SPECIFICATION forming part of Letters Patent No. 761,884, dated June 7, 1904.

Application filed December 3, 1902. Serial No. 133,675. (No model.)

To all whom it may concern:

Be it known that I, HENRY M. HARDING, a citizen of the United States, and a resident of the city, county, and State of New York, have 5 invented certain new and useful Improvements in Telphers, of which the following is a specification.

My invention relates to telphers, and has for its object to provide means for regulating 10 the lowering and hoisting of the bucket containing the material to be carried, and has for a further object means by which the circuit through the motor will be automatically broken and the telpher returned to its starting-place.

In the drawings forming part of this specification, Figure 1 is a view showing diagrammatically one form of my invention. Fig. 2 is a view showing another form of contact 20 making and breaking device. Fig. 3 is a view illustrating the reversing-switch. Fig. 4 is a view showing the lever-arm for breaking the circuit on the rise of the bucket. Fig. 5 is a diagram showing the switch and its connections with the hoisting-motors.

A represents a rail or track on which travels a motor B, the motor receiving its current from a wire C through a trolley D. The motor carries an electric hoisting device consisting of a motor E, which operates a hoisting-drum F, which carries the hoisting-rope G, to which is attached the bucket or receptacle H. I cause the conductor C to be provided with dead sections C' at points where it is desired 35 to stop the motor. Carried by the motor E is a contact-arm E', which when the motor is in the position on the line shown comes in contact with an arm I, which is made of spring metal secured in any convenient manner, so 40 placed that the contact-piece J of the arm E' will be in engagement with it when the motor reaches the position shown. The fixed end of this arm I is in electrical connection through a wire K to the main conductor outside of the 45 dead section. The free end of the arm I is curved upward, so as to afford ready engagement with the contact-piece J of the arm E'. From this it will be seen that when the motor reaches the position shown, the trolley being 50 on the dead section, the motor will stop. At

the same time the contact-piece J, having bearing against the arm I, current is sent through the hoisting-motor from the main line through wire K to piece I, contact-piece J, arm E'. The return-circuit from the motor is not shown.

L represents a switch which is adapted to reverse the hoisting-motor. In the position shown in full lines in Fig. 1 the motor will operate to raise the bucket. I provide the 60 hoisting-rope with a disk N of a size to engage the switch. The circuit being made through the hoisting-motor, the first operation of the motor will be to hoist the bucket; but this motion moves the switch to the position shown in dotted lines on account of the disk N bearing against the switch. When the switch is so moved, it reverses the motor and the bucket is lowered. When the bucket reaches its lowest point, the second disk N', 70 attached to the hoisting-rope, comes in contact with the switch and throws it into the position shown in Fig. 1 in full lines, upon which the motor operates to hoist the bucket. It is desirable, however, that when the bucket 75 rises after discharging its load to have the current cut off from the hoisting-motor and the circuit made through the traveling motor. To accomplish this, I provide the hoisting-rope with a pivoted arm O. This arm is 80 so constructed that while it may move in the upward direction it cannot move below the horizontal. Joints of this kind are so well known that it need not be particularly described. It is, however, clearly illustrated in 85 Fig. 4 of the drawings. As the bucket is lowered, therefore, the arm O being free to rise will pass the arm I, as indicated in dotted lines in Fig. 4. On the ascent of the bucket, however, as this arm cannot fall below the 90 horizontal it will engage the under side of the arm and lift it to the position shown in dotted lines in Fig. 1, thus breaking the circuit through the hoisting-motor. In this position of parts the disk N is just below the 95 switch.

In order that the telpher may be automatically started, I provide a contact-plate P, from which runs a wire Q to the dead section of the main conductor. This contact-plate P is so 100

placed that the end of the piece I will be against it when lifted, as before described and as clearly illustrated in Fig. 1. This results in the current passing from the main conductor through the wire K, piece I, contact-plate P, and wire Q, energizing the dead section of the conductor, thereby causing the traveling motor to move, this motor having previously been reversed by any well-known means—such, for instance, as that shown in the patent to Clift, No. 692,118, January 28, 1902. It will be seen, therefore, that when the telpher has reached the dead section the bucket is automatically lowered and raised, and when it reaches its proper upward position the circuit through the hoisting-motor is broken, and at the same time the current is conveyed to the dead section, thus energizing it and causing the motor of the telpher to move. The relative proportions of parts and their distances from each other are of course much exaggerated, as the illustration is diagrammatic; but the proper placing and proportioning of these parts will be obvious to one skilled in the art.

In Fig. 2 I have shown a modification of the means for breaking the circuit through the hoisting-motor and energizing at the same time the dead section of the main conductor. In this case instead of the piece I, I provide a pivoted arm T, which is pivoted near one end. The shorter end of the arm carries a contact-plate a, which when the arm is in its normal position is in contact with the contact-plate b, which is in electrical connection with the wire K, so that in the position shown in full lines in Fig. 2 the operation as regards the hoisting-motor is the same as heretofore described, the longer part of the arm being sufficiently weighted to keep the arm in the horizontal position. The longer end of the arm carries a metallic contact-piece c, which is insulated from the arm, as shown at d. Attached to the main conductor and outside the dead section is an angular metallic piece e. The contact-piece e is of such a length that when the arm T is in the raised position (shown in the dotted lines) this contact-piece e bridges the space between the metallic piece c and the dead section of the main line, thus conveying the current to said dead section, as will be readily observed. f represents the main switch, through which the current is received from any source of supply, and g represents 55 the wire carrying the current to the main con-

ductor C. It will be observed that either the operation of the hoisting-motor or the operation of the telpher-motor may at any time be stopped by moving this switch.

In Fig. 5 I have shown a common form 60 of switch which may be used with my invention, the connections through the same to the hoisting-motor being shown. This switch is of ordinary form, consisting of a disk h, having contact-pieces i j, with which engage 65 brushes k l m n.

The circuit through the switch and hoisting-motor is as follows: from conductor C through wire K, piece I, contact-piece J, arm E', wire o, brush e, contact-piece i, brush k, wire p to 70 and through the motors E, wire q, brush m, contact-piece j, brush n, wire r to the track-wire A, thus completing the circuit. It will be readily observed that on throwing the switch as described the motor will be reversed. 75

What I claim, and desire to secure by Letters Patent, is—

1. The combination with a telpher and an electric hoisting device carried thereby of means for automatically breaking the circuit 80 through the telpher and establishing the circuit through the hoisting-motor at predetermined points, substantially as described.

2. The combination with an electric hoisting device of automatic means for causing the 85 lowering of the loaded receptacle, automatic means for reversing the motor when the load is discharged, and automatic means for breaking the circuit through the motor when the receptacle has been hoisted, substantially as 90 described.

3. The combination with a telpher having an electric hoisting device, means for breaking the circuit through the telpher-motor and establishing a circuit through the hoisting-motor at predetermined points, automatic 95 means for reversing the hoisting-motor when the bucket thereof is at its lowest point, and automatic means for breaking the circuit through the hoisting-motor and establishing the circuit through the telpher-motor when the bucket has been raised, substantially as 100 described.

In witness whereof I have hereunto set my hand, in the city, county, and State of New 105 York, this 20th day of November, 1902.

HENRY M. HARDING.

In presence of—

LOUIS N. WHEALTON,
WALTER HARTIG.
